DESIGN FOR A DENTAL ACCESSORIES CONTAINER

Alfred A. Einzig, Brooklyn, N. Y.

Application May 18, 1940, Serial No. 92,453

Term of patent 14 years

To all whom it may concern:

Be it known that I, Alfred A. Einzig, a citizen of the United States, residing at Brooklyn, in the county of Kings and State of New York, have invented a new, original, and ornamental Design for a Dental Accessories Container, of which the following is a specification, reference being had to the accompanying drawing, forming part thereof.

cessories container, showing my new design, the cover being shown in closed position.

I claim:

The ornamental design for a dental accessories container, as shown.

ALFRED A. EINZIG.
